UNITED STATES PATENT OFFICE.

JOHN M. ROBERTS AND BRADLEY W. CASE, OF BROWNSVILLE, DAKOTA TERRITORY.

WAGON-STANDARD.

SPECIFICATION forming part of Letters Patent No. 324,958, dated August 25, 1885.

Application filed June 10, 1885. (No model.)

To all whom it may concern:

Be it known that we, JOHN M. ROBERTS and BRADLEY W. CASE, of Brownsville, in the county of Lawrence and Territory of Dakota, 5 have invented certain new and useful Improvements in Wagon-Standards; and we do hereby declare the following to be a full, clear, and exact description of the invention, such as will enable others skilled in the art 10 to which it pertains to make and use it, reference being had to the accompanying drawings, which form part of this specification.

Our invention relates to an improvement in wagon-standards; and it consists in the 15 combination of a bolster having double tenons formed upon its ends with castings which are applied to these ends and bolted in position, and which are provided with double tenons which fit in recesses in the lower ends 20 of the standards, and suitable spring catches which are applied to the standards for the purpose of holding the standards in a vertical position, as will be more fully described hereinafter.

25 The object of our invention is to attach a suitable casting to each end of the bolster, and which are especially adapted for forming a pivot upon which the standards turn when it is desired to move them out of a vertical 30 position to allow the wagon to be loaded or unloaded as may be desired.

Figure 1 is a vertical section of a standard embodying our invention. Fig. 2 is an end view showing the standards in one position 35 in solid lines, and in another position in dotted lines.

A represents a bolster, which has the two tenons B C formed upon each of its ends. The larger tenon fits in the outer end of the 40 socket which is formed in the casting D, while the smaller tenon fits in the small socket which is made in the casting, as shown. This casting is provided with ears which extend along the sides of the bolster, and through 45 which the bolt F is passed; also passed down through the top of the casting, and the larger tenon formed upon the end of the bolster is a second bolt, G, which extends at right angles

to the one F. These two bolts serve to secure the bolster and the casting rigidly together. Formed upon the outer end of the casting is a round tenon, I, upon which the standard J is placed, and which has a hole formed in it for the end of the spring-catch L to snap into, and to hold the vertical standard in a vertical position. Projecting from the outer end of this tenon I is a second and smaller tenon or screw-bolt, N, which projects through the outer side of the standards J, and receives a nut, O, upon it. This smaller 60 tenon or bolt may either be formed in a single piece with the casting, or the casting may be cast upon a screw-threaded bolt which is placed in the mold for this purpose. The nut O prevents the standard from being forced 65 out of position at any time when the standard is turned out of a vertical position. When the standard is in a vertical position, the spring-actuated catch L and the nut together hold it in a position against any lateral strain 70 applied to its inner side. When it is desired to either load the wagon or unload it, or to remove and replace the body, it is only necessary to raise the spring-actuated catch L and then turn the standard around far enough to 75 be out of the way, and then the body or load can be moved without the necessity of raising it up over the top of the standards, and thus save a great deal of labor.

Having thus described our invention, we 80 claim—

The combination of the bolster having the two tenons B C formed upon its ends with the casting having a double socket formed therein and the two tenons upon its outer 85 ends with the bolts, standard, and a catch for holding the standard in a vertical position, substantially as shown and described.

In testimony whereof we affix our signatures in presence of two witnesses.

JOHN M. ROBERTS.
BRADLEY W. CASE.
